Primary Examiner — Brian N Vinson*(74) Attorney, Agent, or Firm* — Prince Heneveld LLP(57) **CLAIM**

The ornamental design for a workwall assembly, as shown and described.

DESCRIPTION

FIG. 1 is a top, front, and right side perspective view of a first embodiment of a workwall assembly showing our new design;

FIG. 2 is a front elevational view thereof;

FIG. 3 is a rear elevational view thereof;

FIG. 4 is a left side elevational view thereof;

FIG. 5 is a top plan view thereof;

FIG. 6 is a top, front, and right side perspective view of a second embodiment of a workwall assembly showing our new design;

FIG. 7 is a front elevational view thereof;

FIG. 8 is a rear elevational view thereof;

FIG. 9 is a left side elevational view thereof; and,

FIG. 10 is a top plan view thereof.

The second embodiment of the assembly is shown broken-away to indicate an unclaimed width, the straight broken-line disclosure is understood to indicate portions of the article in which the claimed design is embodied, but which form no part of the claimed design, and the irregular broken-line disclosure is understood to represent an unclaimed boundary which itself forms no part of the claimed design.
